HOOK AND EYE FASTENER

Gustave T. Stafstrom, Plymouth, Conn., assignor to
Waterbury Buckle Company, Waterbury, Conn.

Filed Dec. 13, 1974, Ser. No. 532,505

Term of patent 14 years

Int. Cl. D2—07

U.S. Cl. D2—418

FIG. 1

FIG. 2

FIG. 3

FIG. 4

FIG. 5

FIG. 7

FIG. 6

FIG. 8

FIG. 9

FIG. 10

FIG. 1 is a perspective view of a hook and eye fastener showing my new design, the two parts of the fastener being shown in unfastened condition.

FIG. 2 is a top view thereof.

FIG. 3 is a side view thereof.

FIG. 4 is a bottom view thereof.

FIG. 5 is an end view thereof showing the left-hand end of the left-hand member of FIG. 2.

FIG. 6 is an end view thereof showing the right-hand end of the left-hand member of FIG. 2.

FIG. 7 is an end view thereof showing the left-hand end of the right-hand member of FIG. 2.

FIG. 8 is an end view thereof showing the right-hand end of the right-hand member of FIG. 2.

FIG. 9 is a top view thereof similar to FIG. 2 but showing the two parts of the fastener in their fastened condition.

FIG. 10 is a vertical sectional view thereof taken on the line 10-10 of FIG. 9.

I claim:

The ornamental design for a hook and eye fastener, as shown and described.
